UNITED STATES PATENT OFFICE.

NAPOLEON B. DOUGLASS, OF OAKLAND, CALIFORNIA.

METHOD OF FORMING HINGE JOINTS.

1,406,727.

Specification of Letters Patent. Patented Feb. 14, 1922.

Application filed January 5, 1921. Serial No. 435,131.

To all whom it may concern:

Be it known that I, NAPOLEON B. DOUGLASS, a citizen of the United States, residing at Oakland, in the county of Alameda and State of California, have invented new and useful Improvements in Methods of Forming Hinge Joints, of which the following is a specification.

This invention relates to the formation of hinge joints between tubular members. In the construction of such articles as folding beds where tubular stock is used, a number of hinge joints have to be provided to allow the legs and other parts to fold. The construction of the hinges used for this purpose in the past has been rather expensive, and the object of the present invention is to simplify the construction of these hinges and produce a satisfactory and inexpensive hinge joint.

In carrying out this object I so cut and shape the end of one tubular member as to form ears thereon which ears are pressed outwardly or spread apart sufficiently to allow the other tubular member to fit between, it being understood that both tubular members are of the same diameter. While the construction is a simple one and may not appear at first glance to involve any problems it is pointed out that this tubular stock is readily susceptible to mutilation and tearing, and being round it becomes a difficult matter to provide punches and dies with proper cutting edges. After long experimentation I have succeeded in producing this type of hinge joint in such a way that the punches and dies do not mutilate or tear the stock and preserve their cutting edges for considerable periods of time.

In the accompanying drawings Fig. 1 shows a side elevation of a hinge joint formed between tubular members such as the present invention is concerned with.

Fig. 2 shows a side elevation of the same taken at right angles to the view shown in Fig. 1.

Fig. 3 shows a side elevation of a similar hinge joint slightly modified so that the hinge members are free to swing in either direction past perpendicular position.

Fig. 4 shows one of the tubular members with longitudinal slots cut therein and representing the first step in my method of producing this hinge,

Fig. 5 shows in a diagrammatic manner a suitable form of punch and die for forming these slots,

Fig. 6 shows a view of one of the tubular members with the material between two of the slots cut away, representing the second step of my method,

Fig. 7 illustrates the same member with the material at the opposite side also cut away,

Fig. 8 illustrates in a diagrammatic way a suitable tool for cutting this material between the slots away,

Fig. 9 shows a view of the tubular member in its finished state, the ears being spread apart or offset sufficiently to receive the end of the adjacent tubular member between them,

Fig. 10 illustrates the suitable form of swedging die for pressing out these ears.

The type of hinge under consideration will now be described in detail. It consists of tubular members A and B of the same diameter. The member A has a pair of ears 10 formed on its end and spread apart to receive the end of the other tubular member 80 between them. A hinge pin 11 is then inserted through openings formed in the ears and in the tubular member B for connecting the parts together. In Figs. 1 and 2 I show a shoulder 12 on the member A to serve as a 85 stop whereby to limit the swinging movement of the hinge members in one direction. In Fig. 3 the material at both sides is cut away so that the members are free to swing in either direction past center.

The steps involved in the production of this hinge are as follows:

First the member A is placed upon a die 13 and four longitudinal slots 15 are cut therein by means of a punch 16. These slots 95 are cut one at a time, and hence no special types of tools are required. Thereafter the material between the slots at two sides is cut away by placing the tubular member upon a punch 17 cooperating with a die 18 100 at the exterior. By having the punch act from the inside the material can be cut away without danger of mutilating or tearing the tube. In case it is desired to form the shoulder 12 at one side then the material is cut 105 away on a straight line slightly above the bottom of the slots. In the case of the opposite side the material is preferably cut

away on an arcuate line. As a result of these operations a tubular member is formed as shown in Fig. 7 having at its end a pair of ears 10. It now becomes necessary to flatten these ears out and to spread them apart sufficiently to allow the end of the other tubular member to fit between. To facilitate the next step the member A is preferably placed in an annealing oven and heated. Thereafter the said member is placed upon a swedging die such as is illustrated in Fig. 10 and the ears are offset and flattened out one at a time. This completes the method with the exception of shaping the ears and punching the holes therefor which may be done in any suitable manner.

A hinge such as is produced by the present invention costs about ten per cent of the cost of prior hinges used for the same purpose. 20 The tools used are in no sense special or difficult to make and they preserve their cutting edges for a considerable period of time. By following the steps herein narrated there is no danger of splitting the tubes or of mutilating them in any way.

Having thus described my invention what I claim and desire to secure by Letters Patent is:—

1. The method of forming a hinge joint 30 between tubular members of the same diameter which consists in cutting longitudinal slots in one of said members, cutting away the material between the slots at two sides thereof, leaving two ears, and thereafter setting the ears out to the extent required to receive the end of the other tubular member.

2. The method of forming a hinge joint 35 between tubular members of the same diam-

eter which consists in cutting four longitudinal slots in the end of the tubular member one at a time, removing two of the strips between the slots leaving two others forming ears at diametrically opposite points and thereafter setting the ears out sufficiently to receive the end of the other tubular member.

3. The method of forming a hinge joint 40 between tubular members of the same diameter which consists in cutting longitudinal slots in one of said members, removing the material between the slots at two sides thereof by means of a punch acting upon the inside of the tubular member, and thereafter flattening and spreading the two remaining 45 portions so as to receive the other tubular member between them.

4. The method of forming a hinge joint 50 between tubular members of the same diameter which consists in cutting longitudinal slots in one of said members, removing the material between the slots at two sides thereof, leaving two ears at diametrically opposite points, heating the tubular member and thereafter spreading the ears apart so as to 55 receive the other tubular member between them.

5. The method of forming a hinge joint 60 between tubular members of the same diameter which consists in first cutting longitudinal slots in the end of one of said members, removing the material between the slots at two sides, leaving two ears at diametrically opposite points, and thereafter offsetting said ears by means of a swedging 65 die.

NAPOLEON B. DOUGLASS.
